Fig. 5

UNITED STATES PATENT OFFICE.

WILLIAM GHIGLIERI, OF SAN FRANCISCO, CALIFORNIA.

TRAFFIC-SIGNAL.

1,224,632.

Specification of Letters Patent.

Patented May 1, 1917.

Application filed January 12, 1915. Serial No. 1,891.

To all whom it may concern:

Be it known that I, WILLIAM GHIGLIERI, a citizen of the United States, residing at San Francisco, in the county of San Francisco and State of California, have invented 5 a new and useful Traffic-Signal, of which the following is a specification.

My invention relates to traffic signals, and the first object of the invention is to provide a traffic signal by which the movement of street traffic may be regulated, particularly at street intersections.

In handling street traffic on crowded city streets it is common practice to station a 15 police officer in the center of the intersecting streets, this officer regulating and controlling the traffic in both streets by the use of a whistle, or other audible signal, and by gestures. The second object of the invention is to provide means by which the officer can control the traffic with greater 20 certainty and by which the traffic will be instantly informed as to the officer's intentions, thus insuring prompt movements of 25 the traffic and greatly reducing misunderstandings and their attendant confusion, delays, and accidents.

Where the officer is stationed on the street his signals are visible and audible over a 30 small area only, and it is impossible for a person approaching the intersection to tell with certainty what the condition is at the intersection until he gets into the immediate neighborhood of the officer. The result is that an automobile, for example, 35 hurries through the space between intersections only to find the traffic blocked at the next corner, thus necessitating a complete stop and a fresh start when the traffic starts again. The third object of my invention 40 is to provide a visible signal which can be seen by all traffic within several blocks of the intersection, so that traffic approaching the intersection will regulate its speed to 45 suit the condition of the signal and thereby avoid stops.

At certain times it is necessary for the traffic officer to leave his post for short periods, and the fourth object of my invention 50 is to provide means whereby the officer can set the signal to operate automatically in his absence, the signal working through a definite cycle automatically.

In our cities the density of traffic during 55 the night on the most used streets, and the

density of traffic at all times on the less frequented streets, is such that the expense of an officer is not warranted, and the traffic is therefore not regulated at such times and places. The fifth object of my invention is 60 to provide a signal which may be entirely automatic and which will control such traffic without the expense of an officer.

It has been found that it is necessary at times to arrest the movement of all traffic 65 to give fire apparatus, or ambulances, the right of way, and the sixth object of my invention is to provide a signal which can be set to stop all traffic if desired.

Where street traffic is handled by a traffic 70 officer, it is common practice for the officer to use a whistle either as a starting or a stopping signal. For example, in some cities a single blast starts the east and west traffic and a double blast starts the north 75 and south traffic. The seventh object of my invention is to provide means for giving audible signals either by bell or whistle and either according to present practice, or otherwise, as may be desired.

There have been devised various forms 80 of traffic signals which are placed on posts; which may be removable, the posts being located in the center of the street. Such posts are objectionable as they obstruct traffic, and the eighth object of my invention 85 is to provide a traffic signal which may be suspended above the center of the street intersection so as not to obstruct in any way the traffic passing over the streets.

In some locations where there are no overhead wires, the use of such overhead signals would be considered unsightly, and the ninth object of my invention is to provide 90 a signal having four displays, each display being secured to a post on the street corner and facing in the direction traffic comes from, the entire four displays being worked together and controlled either automatically or by an officer stationed either in the street 95 or elsewhere.

In the present system of handling traffic each traffic officer is an independent unit working without relation to the adjoining officers. This results in confusion and delays, as traffic cannot move steadily forward. The tenth object of my invention is 100 to provide a signal that is visible to the officer at the next intersection, so that he can regulate his traffic in synchronism there- 105

with, and to provide a series of signals which are operated together when automatically energized.

Further objects and advantages will be evident hereinafter.

In the drawings, which are for illustrative purposes only:

Figure 1 is a side view of the signal as viewed from the south, a portion thereof being broken away to better show the internal structure.

Fig. 2 is a section on the plane x^2-x^3 of Fig. 1, looking in the direction of the arrows.

Fig. 3 is a partial section on the plane x^3-x^4 of Fig. 1, looking in the direction of the arrows.

Fig. 4 is a diagram of a street intersection with a single signal hung in the center of that intersection.

Fig. 5 is an enlarged section on the plane x^6-x^6 of Fig. 2.

Fig. 6 is a partial section on the plane x^7-x^7 of Fig. 6.

Figs. 7, 8 and 9 are diagrams of connections of different signal arrangements.

Fig. 10 is a detail view of the dog means on the end of the reel.

The invention, if assembled as shown in Fig. 1, consists of a rectangular shell 11 in which are placed the displays 12, 13, 14, 15, 16, 17, 18 and 19, these displays being arranged in pairs, the upper signals 12, 13, 14 and 15 being preferably green, and the lower signals 16, 17, 18, and 19 being preferably red. The signals 12 and 16 are so hung that the displays face north, 13 and 17 east, 14 and 18 south, and 15 and 19 west. Inside the case is located a drum switch 20 operated by a magnet 21, a control cable 22 and a changeover switch 23. Suspended on a control cable 24 consisting of two wires is a street switch 25. A vibrating bell 26 is secured in the case 11 and a bell switch 27 is operated from the magnet 21.

The case 11 is preferably formed of galvanized sheet steel and has four sides with a pair of displays on each side. A hood 30 covers each pair of displays so that they are shadowed. Each display consists of an outer lens 31, and inner lens 32, a reflector 33, and a lamp 34. The arrangement and form of the lenses 31 and 32 and the reflector 33 is such that when the lamp 34 is energized, an intense beam of colored light is seen by a person in front of the signal, so that the display is highly colored, and the arrangement of the hood 30 and the lenses 31 and 32 is such that unless the lamp 34 is energized there is no display of the signal, this arrangement being old in the signaling art and forming no part of the present invention.

Obviously other forms of visible displays may be substituted for the form shown.

The reel 22, as illustrated in Fig. 6, con-

sists of a wooden or other insulating cylinder 40 on which are secured metal ends 41 and 42. The control cable 24 is coiled upon the reel 22 when not in use, the end of each of the wires being electrically connected to one of the ends 41 or 42. The end 42 has a stub shaft 43 secured therein, this shaft turning freely in a bearing 44 supported on and insulated from the case 11 by a fiber block 45. A similar bearing 46 is supported on and insulated from the case 11 by a fiber block 47. A shaft 48 is pinned in the bearing 46 extending into a cylindrical hole 49 in the center of the cylinder 40. A bearing 50 is rigidly secured in the cylinder 40, the bearing 50 turning on the shaft 48. A torsion spring 51 surrounds the shaft 48, being secured in the bearing 50, and the end 41. A wheel 52 is secured to the shaft 48 and a pair of dogs 53 are pivoted on pins 54 carried on the end 41. The parts 40 to 54 form the reel 22 which works on the well known principle of the shade roller, winding up any slack when the dogs 53 are released by a quick pull. Current from the control cable is transmitted to the bearings 44 and 46 which are connected as will be further described.

A partition 55 closes the bottom of the case 11 and the control cable 24 passes through an opening 56 therein, a hard wood block 57 being secured over the opening, this block having an opening 58 with rounded edges through which the cable 24 passes to prevent fraying.

The changeover switch 23 is preferably a pull switch of any well known form having a chain 59 and a ring 60, this ring hanging slightly below the lower end of the case 11. Any type of pull switch which will connect a single wire to a primary wire with one pull, a secondary wire with a second pull, back to the primary wire with a third pull, and so on, will be acceptable, there being many switches of this type on the market. A diagram of this switch is shown at 23 in Fig. 10.

The street switch 25 is a push switch having a single button which connects a circuit on the first push, opens the circuit on the second push, closes the circuit on the third push, and so on, there also being many types of switch of this character on the market. A diagram of this switch is shown at 25 in Figs. 8 and 10.

The bell 26 may be any ordinary vibrating bell, or an electrically operated whistle may be substituted therefor.

The drum switch 20 and its operating magnet 21 are especially designed for the particular service to be performed, and the exact structure shown can be modified to suit other requirements. As shown it consists of a cast iron base 70 having operating shaft bearings 71 formed thereon in which 130

an operating shaft 72 turns, and having drum shaft bearings 73 in which a drum shaft 74 turns. Secured to the drum shaft 74 by metal ends 75 is an insulating drum 76 which has a conducting cylinder 77 secured thereon. An insulating base 78 secured to the cast iron base 70 carries fingers 81, 82, 83, 86, 87 and 88 which press upon and make electrical connection with the cylinder 77.

In Figs. 7, 8 and 9 developments of the cylinder 77 are shown in which holes 89 and 90 are shown cut in the cylinder 77 in the path of the fingers 82 and 83, holes 91 and 92 being similarly cut in the cylinder 77 in the path of the fingers 86 and 87. The cylinder 77 is cut away in the path of the finger 81 to form contact spaces 93, 94, 95 and 96. The cylinder 77 is intact under the finger 88.

Secured in one of the metal ends 75 of the drum 76 are ten equally spaced pins 100 which project slightly from the end 75 into the path of a trigger 101 which is pivoted on a pin 102 carried on an arm 103 secured to the shaft 72. A spring 104 holds the trigger 101 in engagement with one of the pins 100. A latch 105 is pivoted on a pin 106 carried in a bearing 107 secured to the insulating base 70. When the shaft 72 turns in a counterclockwise direction the drum is pulled around by the trigger 101, and as the shaft 72 turns in the opposite direction the latch 105 prevents a movement of the drum, the trigger 101 sliding over the next pin 100 which it engages at its extreme position.

The magnet 21 consists of a winding 108 which magnetizes a core 109 which attracts an armature 110, this armature being rigidly secured to the shaft 72, and turning this shaft 72 and the arm 103 when the armature is attracted by the core. The bell switch 27 consists of an insulating block 111 secured to the cast iron base 70 and carrying a pair of jaws 112. A blade 113 makes contact with the jaws 112 when the armature 110 strikes the core 109, the blade 113 being carried on an insulating block 114 carried on an arm 115 which is also secured to the shaft 72.

In practice I connect the signals in any one of three ways, as shown in Figs. 7, 8 and 9. In Fig. 9 I show a complete signal with street, and changeover switch, this signal being connected to the supply mains 150 and 151 and to the control wire 152 by a suitable manipulation of the changeover switch. This type of signal and method of connection is intended for use where it is necessary to have an officer a portion of the time, but where it is desired to switch over the signal to operate on a regular cycle whenever necessary, in which case the officer is not needed.

In Fig. 8 is shown a purely automatic

control, the officer having no control of the signal which operates at stated intervals. In this type the switch 25, the cable 24, the drum 22, and the changeover switch 23 are all omitted.

In Fig. 8 is shown a switch for purely manual control, the changeover switch 23 being omitted.

The method of connection is as follows:

The displays 16 and 18, 17 and 19, 12 and 14, and 13 and 15, are connected in pairs, either in multiple or series, one terminal of each pair being connected to the wire 151 and the other terminals being connected as follows: Lamp 18 to finger 86, lamp 19 to finger 87, lamp 14 to finger 82, lamp 15 to finger 83. Finger 88 is connected to wire 150 and finger 81 to one of the jaws 112 of the bell switch 27, the other jaw 112 being connected to the magnets of the bell 26. The above connections are common to all the forms illustrated in Figs. 7, 8 and 9. In the form illustrated in Fig. 9 one side of the magnet winding 108 is connected to the wire 150, and the other side is connected to the center 155 of the changeover switch 23 to which the other side of the bell winding is also connected. By suitably manipulating the switch 23 the center 155 can be connected to the contact 156 connecting to the control wire 152 or to the contact 157 connecting through the street switch 25 with the wire 151. Contacts 158 of a time switch, are closed at predetermined times and for predetermined intervals by a connecting member 159 actuated by a clock, or other means, not shown, for the purpose of energizing the control wire 152 from the wire 151.

In Fig. 8 the switches 23 and 25 are omitted, the magnet winding 108 being directly connected to the wires 150 and 152.

In Fig. 7 the magnet winding 108 is connected to the wires 150 and 151 through the switch 25 the changeover switch 23 being omitted.

The systems of connection illustrated in Figs. 7, 8 and 9 are all designed to operate the signals in the same manner, the cycle being as follows: First, a short series of rings from the bell accompanied by a green display 110 east and west and a red display north and south, this starting the east and west traffic. Second, a change to red on all four sides without a bell signal, thus stopping the east and west traffic. Third, two short series of rings from the bell with green displays 115 north and south and red displays east and west, this starting the north and south traffic. Fourth, a change to red on all four sides without a bell signal, thus stopping the 120 north and south traffic. This cycle is then repeated.

The method of operation of the system shown in Fig. 9 is as follows: When the officer comes on duty he takes a rod or wire and 130

pulls the switch 25 down to a convenient length, unwinding the control cable 24 from the reel 22, the dogs 53 holding the reel stationary if desired. He then pulls the chain 59 by means of the ring 60 throwing the changeover switch into the position shown in full lines in Fig. 9. He then closes the switch 25 sending current through the winding 108 and drawing the armature 110 10 against the core 109. This turns the shaft 72 and the arm 103 and pulls the drum switch over thirty-six degrees by means of the trigger 101 and the pins 100. This moves the drum development in the direction of the 15 arrow in Fig. 9 into the position shown in that figure, the fingers 81, 82, 83, 86, 87 and 88 resting on the line α^1 . When the armature 110 strikes the core 109 the blade 113 of the bell switch 27 makes contact with the 20 jaws 112 and current flows from the wire 151 through the switch 25, the contacts 157 and 155 of the switch 23 through the bell 26 to the finger 81, through the contact 93 to the cylinder 77, and through the finger 88 to the 25 wire 150, the bell ringing until the officer opens the switch 25, when the bell stops and the weight of the armature 110 causes the shaft 72 and its connected parts to resume their initial position, as shown in Figs. 1 30 and 6. The officer immediately closes the switch 25 again, causing a second ring, and a second actuation of the drum takes place, the fingers resting on the line α^2 . In this position the fingers 87 and 82 energize, and displays 17, 19, 12 and 14 are shown, or green 35 signals show N and S and red signals E and W. The bell rings until the officer opens the switch 25, thus releasing the armature again, the drum remaining in position α^2 .

40 When the officer desires to stop the N and S traffic he again closes the switch 25, thus energizing the coil 108 and actuating the drum switch, the fingers moving to the position α^3 . The finger 81 slides off the contact 45 93 before the blade 113 closes the bell circuit through the jaws 112, so that the bell does not ring as the drum switch turns to the position α^3 . In this position contacts 86 and 87 are energized and displays 16, 17, 18 and 50 19 are shown, or all displays are red.

55 After a certain interval if the officer wishes to start the E and W traffic, he closes the switch 25, energizing the coil 108 and pulling the drum switch into the position α^4 . As the blade 113 closes the contacts 112 and the finger 81 slides on the contact 94, the bell starts to ring, ringing until the officer opens the switch 25, allowing the armature to resume its original position, 60 the drum remaining in the position α^4 . In the position α^4 the fingers 86 and 83 are energized and the signals 16, 18, 13 and 15 are energized or N and S are red and E and W are green. When the officer wishes to stop 65 the E and W traffic he closes the switch 25,

thus pulling the drum development to the position α^5 . As the finger 81 moves off the contact 94 before the blade 113 closes the bell circuit through the jaws 112, the bell does not ring as the drum goes to position α^5 . In the position α^5 the fingers 86 and 87 are energized and the displays 16, 18, 17 and 19 are energized, thus making all signals red.

70 When the officer wishes to start the N and S traffic he closes the switch 25, thus throwing the drum switch to the position α^6 . As the finger 81 passes on the contact 95, the bell rings, continuing until the switch 25 is opened by the officer, who immediately 80 closes the switch 25, pulling the drum switch to the position α^7 and ringing the bell until the switch 25 is opened again. In the position α^7 the fingers 87 and 82 are energized and displays 17, 19, 12 and 14 are shown, or 85 red E and W and green N and S.

Positions α^8 and α^9 correspond to positions α^1 and α^2 and a further actuation of the signal repeats the cycle.

90 When it is desired to work one or more signals automatically without an officer, the changeover switch 23 is actuated to connect the center 155 with the contact 156, thus disconnecting the coil 108 from the street switch 25 and connecting it to the control 95 wire 152. This wire is connected to the wire 151 at time intervals that correspond to the intervals produced by the officer's manipulation, as previously described, so that the signal goes through the cycle previously explained automatically. The contact 159 is actuated for this purpose by any convenient form of time switch, or other means, not shown.

100 In certain locations an officer is not necessary, in which case the signal is connected as shown in Fig. 8, the coil 108 being absolutely controlled at all times by the control wire 152 which is energized at regular intervals by the time switch, as previously explained.

110 On the other hand, where no automatic operation is required, the control wire 152 and changeover switch 23 may be omitted, the parts being connected as in Fig. 7.

115 I claim as my invention:

1. A traffic signal comprising a plurality of visible displays, means for exhibiting said displays, manual means by which a traffic officer may control the exhibition of 120 said displays, and means by which the displays may be automatically changed at regular intervals in the absence of the officer.

125 2. A traffic signal comprising a plurality of visible displays, means for exhibiting said displays, manual means by which a traffic officer may control the exhibition of said displays, means by which the displays may be automatically changed at regular intervals in the absence of the officer, and means by 130

which the traffic officer can throw the control of the signal from the automatic means to the manual means or vice versa.

3. A traffic signal comprising a plurality of sensible indication means, means by which a traffic officer may control the operation of said indication means at such intervals as he may desire; and means by which said officer can cause said indication means to 10 actuate at regular intervals without specific attention from him.

4. An electrically operated traffic control system comprising a plurality of signals;

means by which traffic officers may independently control the operation of any or 15 all signals; and means by which the traffic officers can cause all or a part of said signals to operate automatically at regular intervals.

In testimony whereof, I have hereunto set my hand at Los Angeles, California, this 20 30th day of December, 1914.

WILLIAM GHIGLIERI.

In presence of—

FORD W. HARRIS,

FRANK L. A. GRAHAM.
